RADIO ACTIVE ELECTRODE CONSTRUCTION

Kurt Lehovec, Williamstown, Mass., assignor to Sprague Electric Company, North Adams, Mass., a corporation of Massachusetts

Application June 25, 1953, Serial No. 364,006

3 Claims. (Cl. 317—235)

The present invention relates to a new and improved type of electrode construction which is primarily useful with transistors.

One type of transistor consists of a body of a semi-conductive material to which there is attached a low resistance electrode, and against which is pressed two other point contacts termed the emitter and the collector, respectively. There is a need for improving the effectiveness of either or both of these last electrodes. In order to accomplish such ends, forming procedures, such as are mentioned in the Wallace Patent No. 2,563,503, have been recommended particularly for the collector electrode. While such procedures are effective, they, nevertheless, do not provide point contact arrangements of the desired effectiveness.

It is an object of the instant invention to improve upon the foregoing and related prior art. A further object of the invention is to manufacture highly efficient transistors. These and other objects of the invention, as well as its advantages will be apparent from this description, the accompanying claims, as well as the accompanying drawing.

This drawing diagrammatically shows the type of construction employed with the instant invention.

This consists primarily of a body of a semi-conductive material 10, such as, for example, n-type germanium, which has been provided on one surface with a low resistance metallic layer 11, such as, for example, a rhodium layer of from 0.0001 to 0.01 inch in thickness by plating. Against another surface of the semi-conductive body 10, two wire electrodes 12 and 13 are positioned in accordance with known procedures.

At least one of these two electrodes 12 and 13 used with the present invention differs from the prior art probes in that it is provided with a source of alpha particles so as to bombard the adjacent surface of the semi-conductor with the same particles in order to alter the type of conduction of the semi-conductor. Preferably, the semi-conductors used with the present invention are of the n-type germanium, and a p-n junction is formed adjacent to the electrodes by bombardment from the alpha particle source.

The source of alpha particles is, of course, capable of variation. A preferred source is polonium metal which has been plated upon the external surface of the wire probe. Alternately, the probes can consist of a substantially hollow tube, the center of which is filled with the same metal or another type of source.

It has been known for quite some time that the electrical conductivity of a semi-conductor could be altered by particle bombardment. As an example of this reference is made to the Lark-Horovitz Patent No. 2,588,254, relating to a device comprising a unitary body of germanium having a plurality of p-n type junctions through-

2

out its length. Reference is also made to the text "Semi-Conductor Materials" published in 1951 by Academic Press, Inc., of New York. On page 66 of this last reference alpha particles, deuterons, neutrons, and fast electrons are indicated as types of radiation which can change n-type germanium to p-type germanium, and which can increase the conductivity of the p-type germanium. Nowhere in any of these or other references is there any indication that a thin layer could be created adjacent to point contacts by the means described.

It will be realized by those skilled in the art that the inclusion of an alpha particle source upon the collector of the transistor utilizing an n-type germanium body serves to create a p-n boundary close to the collector probe. The depth of this boundary varies with the quantity of alpha particles available for bombardment. Thus, it is believed that the beneficial results of the present invention are similar to the results obtained by electrical forming of the collector of a transistor. It will be further realized by those skilled in the art that this separate forming step is not necessary with the particular constructions herein set forth, and that the described units can be easily and conveniently produced on a mass production scale.

Further, those skilled in the art will realize that the invention is not limited to the use of polonium as an alpha particle source. Other sources, such as thorium, thorium carbide, and the like, can also be used. Similarly, other semi-conductive materials besides germanium, such as, for example, silicon or silicon carbide can be used with the invention.

As many apparently widely different embodiments of my invention may be made without departing from the spirit and scope hereof, it is to be understood that my invention is not limited to the specific embodiments hereof except as defined in the appended claims.

What is claimed is:

1. In a point-contact transistor having a body of n-type conductivity, a base electrode in ohmic contact with said body, an emitter electrode in rectifying contact with said body, and a collector electrode in contact with said body in close proximity to said emitter electrode; the improvement comprising providing said collector electrode with a source of alpha-particle radiation so as to produce a region of p-type conductivity in said body surrounding said collector contact.
2. A wire probe for a transistor which comprises a central conductive core around which is plated a thin layer of polonium.
3. A transistor comprising a body of n-type germanium, a low resistance base electrode attached to said body, and a wire probe bearing against said body, said wire probe being plated with a layer of alpha-particle-emitting polonium to create a permanent p-n junction within the germanium adjacent to said probe.
